HAIR CURLING APPARATUS

Filed Aug. 23, 1928

UNITED STATES PATENT OFFICE

PAUL KUNIN AND ISAAC E. MCELROY, OF MINNEAPOLIS, MINNESOTA; SAID MCELROY
ASSIGNOR TO SAID KUNIN

HAIR CURLING APPARATUS

Application filed August 23, 1928. Serial No. 301,546.

This invention relates to apparatus used in curling human hair and especially to apparatus for effecting so-called permanent waves.

It is an object of our invention to provide 5 highly efficient apparatus for quickly and accurately winding and retaining a lock of hair about a stem or rod for the purpose of curling the hair or in connection with other apparatus for effecting a so-called permanent 10 wave.

It is a further object to provide simple and efficient apparatus for curling human hair which will detachably clamp a lock of hair and cause the same to be quickly and evenly 15 wound upon a curling rod by the easy manipulation of a winding element engaging the rod.

It is another object of the invention to provide in apparatus of the class described, a 20 winding device co-operating with a curling rod which will quickly wind a lock of hair about the rod, progressing itself upon the rod when rotated, by its engagement with a lock of hair.

25 Another object is to provide a winding device of the class described, which will wind a lock of hair upon a rod, placing a uniform tension on the lock throughout its length regardless of the thickness of the lock, within, 30 of course, reasonable limits.

Another object is to provide apparatus of the class described, by which a lock of hair may be simultaneously wound about a curling rod and secured thereto in position for 35 curling.

A still further object of the invention is to provide a novel method for winding a lock of hair about a rod effecting a so-called permanent wave and simultaneously with said 40 winding, retaining the lock or curl by applying a spiral or metal strip.

A further object is to provide in apparatus of the class described an efficient clamping shield, adapted to be quickly and easily secured to locks of hair of various sizes within certain limits and carrying thereon means for quickly connecting therewith a curling rod, upon which the lock may be wound.

50 These and other objects and advantages of the invention will be apparent from the fol-

lowing description made in connection with the accompanying drawings in which like reference characters refer to similar parts throughout the several views and in which:

Fig. 1 is a side elevation of an embodiment 55 of my clamping shield, shown affixed to a lock of human hair adjacent the scalp;

Fig. 2 is a similar view showing the shield applied to the hair and having the curling rod detachably connected therewith; 60

Fig. 3 is a side elevation showing the lock of hair wound about the rod by means of my improved winding element, said winding element being shown in retaining position after the lock has been wound in full lines, and being shown in initial or starting position to wind, in dotted lines; 65

Fig. 4 is a side elevation of a heating unit 70 for steaming and drying the wound lock of hair having my apparatus releasably connected thereto, the rod and lock of hair being disposed therewithin;

Fig. 5 is a top plan view of a rod showing the yielding retaining means for releasably securing the rod, lock and shield to a tubular 75 heater;

Fig. 6 is a perspective view of my preferred winding element detached;

Fig. 7 is a plan view of one form of my clamping shield showing the pivoted sections 80 in closed position in full lines and one of the sections in open position in dotted lines;

Fig. 8 is a cross section taken on the line 8—8 of Fig. 7;

Fig. 9 is a cross section taken on the line 85 9—9 of Fig. 7;

Fig. 10 is a side elevation of my winding element detached showing the means for uniformly tensioning the hair during the winding thereof; 90

Fig. 11 is a bottom plan view of the same.

Fig. 12 is a top plan view of a slightly different form of clamping shield than that shown in Fig. 7; and

Fig. 13 is a side elevation illustrating the manner in which a strip of wire or metal foil may be wound conjointly with a lock of hair to secure the lock in coiled position with my apparatus.

As shown in the drawings, our apparatus 100

includes a clamping shield which is adapted to be secured about a lock of hair adjacent the scalp, comprising, as shown in Figs. 7, 8 and 9 a pair of hinged sections 13 and 14 respectively, said sections being of substantially arcuate shape and one thereof comprising a pair of similarly shaped plates spaced a short distance apart by suitable means, between which plates the other or inner section 14 is adapted to pass when the device is closed. One of the sections, preferably the inner section 14 carries an upstanding stud 15 which may have a transverse pin 16 passed therethrough if desired to assist in connecting said stud with a curling rod to be later described. Sections 13 and 14 are hinged together at their inner and overlapping ends by suitable means, such as a pin 17. The inner edge of the section 13 has a portion substantially concentric with stud 15 and the inner section 14 also has a portion of its inner edge adjacent stud 15 concentric therewith to permit a lock of hair to be clamped between said opposing edges and to be drawn toward and about stud 15. A narrow up-standing flange 13a is provided on the outer section 13 disposed substantially concentric of stud 15 when the sections are in closed position, the purpose of which is to prevent a lock of hair from being disposed flat against the surface of the section 13.

Section 13 is provided with an operating handle 13b, while section 14 is provided with an operating handle 14b, said handles being disposed adjacent the respective outer ends of said clamping members. Between the plates of section 13 is pivotally secured a pawl 18 urged inwardly by suitable means, such as a small leaf spring 19 disposed between the plates, and said pawl is adapted to engage teeth 14a which may be formed on the outer edge of the inner section 14. The outer edge of section 14 is so shaped that when it is swung, any of the teeth 14a will be properly positioned during the closing movement to engage said pawl. Pawl 18 is provided with an outwardly projected operating handle 18a and the pawl may be released by pressing the handles 18a and 13b together, thus releasing the inner member 14 so that the clamping sections may be swung apart.

We provide a straight substantially cylindrical curling rod 20 which is preferably of tubular structure and of such dimension as to nicely fit over the stud 15. If desired, the lower end of rod 20 may be slotted as shown in Fig. 5 and an enlarged portion formed in the slot adapted to accommodate the pin 16 on stud 15. By pushing the lower end of rod 20 over stud 15, the slot being first alined with the pin 16, it will be seen that the rod may be secured to the clamping shield extending substantially normal thereto.

We provide a novel winding element, designated as an entirety by the letter W, which may be formed integrally comprising a tubu-

lar portion 21 adapted to surround the rod 20 and having connected therewith and spaced at some distance therefrom a substantially tubular winding handle 22, which may have outwardly projecting ears to facilitate the manipulation thereof. The tubular portion of my winding element 21 carries a spiral winding tongue 23 of considerable length curved in the manner of a spring harrow tooth about the tubular portion 21 and having an inclined spiral upper edge 23a, a V-shaped tip 23b and a slightly inclined lower edge 23c. The inner and wider end of the winding tongue 23 has at its upper edge a slightly declined slotted portion 23d, and immediately adjacent the closed end of slotted portion 23d a bulge y is formed in the body of the winding tongue 23, which bulge in connection with said slotted portion 23d has a very important function to be later described. A yielding or resilient tensioning element is wound with the spiral tongue 23, as shown, comprising a spiral spring 24, which may be anchored at one end by means of a pin 25 to the body of tongue 23 and further anchored at its tip 24a in a small recess in the tongue 23. Spring 24 has a true spiral upper edge x and extends about the rear portion of the spiral tongue 23 shown in Fig. 3 and has a free and yielding inner end 24b which is disposed below the tubular portion 21 of the winding element and projected slightly inwardly thereof adapted to engage the hair and apply a pressure or tension to the hair in co-operation with the rod 20.

When the lock of hair is completely wound upon the rod, as shown in Fig. 3, our winding device W may be left upon the rod if sufficient winding devices are provided for the number of rods needed to wave a full head of hair and said winding devices will then retain the wound locks. The rod and clamping shield with the lock of hair thereon may be detachably secured within a suitable tubular heating unit, shown in Fig. 4. The heating unit shown comprises a tubular casing 26 having super-imposed at the lower or intermediate portion thereof, an outer tubular casing 27 and between casings 27 and 26 an electrical heating element 28 of suitable construction may be interposed. The rod 20 is somewhat longer than the tubular casing 26 and has at its upper end a pair of curved spring retainers 20a, which both may be constructed from a single piece of spring wire, as illustrated in Figs. 2 and 5. The retaining clips have arms extending upwardly from a central loop portion which may be fixed within the tubular rod 20 by means of a pin 20b. The clips terminate in outwardly curved portions which may project through small oppositely disposed slots 20c adjacent the upper end of the rod 20. The upper end of the heater casing 26 is provided with a diminished portion 26a having

Operation

The operation of our apparatus may be briefly stated as follows:

The clamping shield is first opened by releasing engagement of the locking pawl with the notches or teeth on the adjacent edge of the other hinged section and the shield is then placed around a lock of hair near the scalp and the sections pressed together. The 70 spring pressed pawl engages in the teeth and by manipulation of the handles of the two sections the lock may be tightly clamped between the two sections and adjacent the upstanding stud. The curling rod 20 is next 75 attached to the upstanding stud by alining the slots with the pin on the stud and the winding device W is slipped over rod 20 and positioned against the clamping shield. Upon rotation of the spiral winding device 80 the elongated curved tongue 23 will surround the lock of hair it being impossible for any strands of hair to fall flat against the shield because of the narrow arcuate flange 13a adjacent the stud. As the spiral winding device 85 is rotated the lock of hair is drawn inwardly by the inclined edge 23a of tongue 23, being compacted against the rod and subjected to the pressure of the resilient tensioning member 24. Tension is applied between the free 90 end 24b of the tensioning member and the rod. The free end of the lock extends from the winding device through the slightly declined slotted portion 23d (see Figs. 3 and 6) and is 95 also engaged and effected by the bulge y adjacent the end of said slotted portion, as well as by the true spiral edge z of the spring member 24. The rotation of the device W causes the device to progress upon the rod through its engagement with the lock of hair. The 100 base and relation of the bulge or enlargement y with the slot 23d determines the form of the coiled lock. Thus, the lock can be half 105 twisted to form a so-called flat curl, or can be completely twisted as it is coiled about the rod. The bulge is spirally angled with relation to the tongue 23 and slot 23d. It is, of course, well known that the lock of hair diminishes in thickness at its outer end since some of the strands are longer than others and it is, therefore, necessary to apply the same 110 tension throughout the length of the lock if the lock is to be properly wound upon the rod for waving. Because of the resiliency and construction of our spring tension member 24, 115 a nearly uniform tension is maintained upon the lock throughout the length thereof and upon locks of different dimensions. The lock is thus evenly and perfectly wound upon the rod by the use of our winding device W, and due to the tension and cooperation of the resilient member 24, the coils of hair will be 120 formed in true spirals and will not bunch or pile up about each other. 125

In Fig. 4 a pad 30 for applying a moistening solution to the curl is shown wrapped about the lock of hair on the rod and having its upper and lower ends crimped against the rod. This pad may be of any suitable form, such as the pad disclosed in Patent No. 1,659,490, entitled "Permanent wave pad", 30 issued February 14th, 1928, to Paul Kunin, one of the joint inventors in this application.

In Fig. 12, a different form of clamping shield than that previously described is illustrated. This form comprises a pair of curved 35 hinged sections 31 and 32, the outer section 32 of which may comprise a pair of similarly shaped plates disposed one above the other and spaced apart to permit reception of the inner section 31. Section 31 has a diminished 40 inwardly projecting arm 31a shaped in such manner that it will always be disposed within and hidden by the spaced plates of section 32. Sections 31 and 32 are pivoted together by a suitable pin 33, which passes through the 45 inner end of section 32 and the intermediate portion of section 31. The arm 31a of the inner section 31 is provided with a curved edge 31b which may be notched for locking engagement with a pawl 34 pivoted between the 50 spaced plates of section 32 and pressed by a suitable spring 35 into engagement with the teeth or notches on the edge 31b of section 31. An upstanding stud 36 is carried by one of the sections, preferably the inner section 31 55 for securing one of the rods 20, and the edges of the section adjacent stud 36 are formed in the manner of the edges of the clamping shield illustrated in Fig. 7. The form of clamping shield just described has an advantage 60 over the clamping shield shown in Fig. 7, in that the teeth or notched portions on the inner section are covered and entirely hidden by the outer section 32, thereby preventing strands of hair from engaging the 65 teeth or notches.

In waving a head of hair, a plurality of 130

- rods, shields and heaters are used, each receiving and curling one lock of hair. If winding devices W are provided for all the rods they may be left on the rod after the hair is wound to retain the coil of hair. The rod, the curled lock and winding device may then be surrounded with a suitable permanent wave pad, such as the kind disclosed in said U. S. Patent 1,659,490, and the rod may be inserted through the tubular heater, the upper end of the rod passing through the diminished opening in the upper end of the heater and the spring clips 20a releasably securing the rod, shield and curl within the tubular heater through their engagement with the upper edge of the opening of the heater.
- From the foregoing description it will be seen that clamping shields unencumbered by the rods may be quickly and easily clamped to the respective locks of hair adjacent the scalp without discomforting the subject, the structure of said clamping shields rendering them adjustable to tightly clamp locks varying widely in thickness. It will be further seen that the rods 20 may be quickly and easily connected with the studs 15 or 36 of the clamping shields, that by slipping the winding devices on the rods and twisting or rotating the devices W through a few rotations, the locks of hair will be perfectly wound for treatment on the rod.
- It is often the case that only one winding device W is supplied with a complete set of apparatus, including a plurality of rods, clamping shields, and heaters and in this case, it is necessary to remove the winding device from the rods after the locks are curled and consequently means must be supplied for retaining the coiled lock to the rod. We have invented a new method for doing this, which method may be easily and quickly carried out by the use of our winding element. As shown in Fig. 13, a strip or thin wire M of some relatively heavy material, which may be easily bent and which will tend to retain its shape, such as aluminum foil or some other metallic substance may be supplied and clamped, as shown in Fig. 13 with a lock of hair, by the clamping shield and extending along the lock of hair to be wound. The winding device is then applied and will wind with the lock of hair the strip or wire of heavy material, this wire being super-imposed above the hair by the action of the winding device and being quickly formed in the shape of a spiral coil firmly holding the hair coiled around the rod. When the lock is completely wound the free end of the strip M may be completely wound by a few additional rotations of the winding device. The winding device may then be removed and the coil of hair will be secured to the rod. The strip or metallic wire may, of course, be wound about the curl manually or in any manner, but to our knowledge it is new in the art to employ an elongated strip of

metal to be wound with and about a lock of hair on a rod to retain the hair in operative position to be waved. By our method and the structure in co-operation of our clamping shield, flexible metal strip and rod, the separated locks of hair may be quickly coiled about the rods and secured thereto readily for the steaming and drying treatment within the tubular heaters.

From the foregoing description it will be seen that we have invented a simple and highly efficient apparatus for curling and waving human hair adapted to be used in connection with standard types of permanent wave machinery now on the market. With the use of our apparatus a great saving may be made in time and labor and the locks of hair will be wound with a uniform tension to the very end of the lock.

It will, of course, be understood that various changes may be made in the form, details, arrangement and proportions of the parts without departing from the scope of applicants' invention.

What is claimed is:

1. In apparatus for curling hair, a clamping shield comprising a pair of clamping sections having ends pivoted together, one of said sections having a slotted portion adapted to accommodate said other section when said sections are swung together, said slotted section having a pawl and said other section having a plurality of locking elements engageable by said pawl to secure said sections together about a lock of hair in a variety of different positions, one of said sections being adapted to carry a curling rod, both of said sections having inner edges extending substantially concentric with said rod for accommodation of a lock of hair and one of said sections having an upstanding flange disposed concentrically of said rod and spaced therefrom when said sections are secured together to prevent strands of hair from falling flat against the shield and a winding device comprising a spiral tongue rotatably mounted on said rod and adapted to cooperate with said upstanding flange to engage and wrap the hair about said rod when rotated.

2. In apparatus for curling hair, a curling rod, means adjacent one end of said rod for detachably securing a lock of hair thereto, a winding device comprising a spiral tongue adapted to encircle said rod and engage said lock of hair when rotated, said tongue having an inclined spiral upper edge and a resilient tensioning element comprising a tongue secured at its outer end to the outer portion of said first mentioned tongue with its inner end partially wound about said rod and free to apply tension in the direction of said rod as said winding device is rotated.

3. In apparatus for curling hair, a curling rod, means adjacent the end of said rod for detachably securing a lock of hair thereto, a

winding device comprising a substantially annular portion adapted to encircle said rod, a spiral tongue rigidly connected with said annular portion adapted to encircle and engage a lock of hair when said winding device is rotated and a spiral shaped resilient plate connected at its outer end with the outer portion of said tongue and partially wrapped about said tongue and having its inner end disposed in a recess in said tongue positioned to engage said lock of hair and apply a substantially uniform tension thereon as said winding device is turned.

4. In apparatus for curling hair, a curling rod, means adjacent one end of said rod for detachably securing a lock of hair thereto, a winding device comprising a substantially annular upper portion adapted to surround said rod, a spiral tongue rigidly secured to said inner portion and having a free outer end adapted to encircle a lock of hair when the said winding device is rotated, said tongue having a spiral upper edge terminating in a slotted portion for confining and guiding the hair, said tongue having a recessed portion adjacent the inner and attached end thereof and a resilient plate secured to the exterior of said tongue and spiraled therearound, the inner end of said plate being disposed in said recessed portion of said tongue and being free to press against the lock of hair to apply substantially uniform tension thereon throughout the length of said lock.

35 5. In apparatus for curling hair, a curling rod having a tubular upper end adapted for insertion in a tubular heater, a resilient retaining element disposed within the tubular end of said rod and having a projection working through said rod, said projection being depressed upon insertion of said rod in said heater until it snaps past the inner end of said heater, then projecting to retain said rod.

45 6. In apparatus for curling hair, a curling rod having a tubular inner end adapted for insertion in a tubular heater, spring retaining elements anchored within the tubular end of said rod comprising individual springs having looped free extremities which project through slots in said rod, said projecting portions being engageable with the inner portion of said tubular heater to secure said rod in said heater.

55 7. The method of preparing hair for permanent waving which consists in conjointly winding about a rod a lock of hair and an elongated piece of flexible material of a nature adapted to retain its shape when bent, said flexible material being wound outside of the lock of hair to secure the same in coiled arrangement about the rod.

In testimony whereof we affix our signatures.

PAUL KUNIN.
ISAAC E. McELROY.
